FIG. 1

7 2 9 - 2

A unit is enclosed within the broken lines on the drawing, which unit is repeated in regular succession as indicated by the extension beyond the unit boundaries.

We claim:

The ornamental design for a hard surface floor covering or similar article, substantially as shown and described.
